Primary Examiner — Eliza Z Bennett-Hattan(74) *Attorney, Agent, or Firm* — 3M Innovative Properties Company; Jonathan V. Sry(57) **CLAIM**

The ornamental design for a stethoscope chestpiece, as shown and described.

DESCRIPTION

FIG. 1 is a perspective view showing the new design of a stethoscope chestpiece;

FIG. 2 is a back view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The portions of the stethoscope chestpiece in FIGS. 1-7 shown in dashed broken lines are included to show features that form no part of the claimed design.

1 Claim, 5 Drawing Sheets(56)
